(57) **CLAIM**

The ornamental design for a switch block, as shown and described.

DESCRIPTION

FIG. 1 is a perspective view of a switch block, showing my new design;

FIG. 2 is a front elevational view thereof;

FIG. 3 is a rear elevational view thereof;

FIG. 4 is a left-side elevational view thereof; the right-side elevational view being a mirror image thereto;

FIG. 5 is a top plan view thereof; and,

FIG. 6 is a bottom plan view thereof.

The broken line portion of the figure drawings is included to show unclaimed subject matter only and forms no part of the claimed design.
